Patented Nov. 9, 1920.

INVENTOR
JOHN KERN:

BY
W. G. Sandell

ATTORNEY

UNITED STATES PATENT OFFICE.

JOHN KERN, OF LOS ANGELES, CALIFORNIA.

REFLECTOR-MOUNTING.

1,358,159.

Specification of Letters Patent.

Patented Nov. 9, 1920.

Application filed March 9, 1920. Serial No. 364,410.

To all whom it may concern:

Be it known that I, JOHN KERN, a citizen of the United States, residing at Los Angeles, in the county of Los Angeles and State of California, have invented new and useful Improvements in Reflector-Mountings, of which the following is a specification.

This invention relates to a reflector and a mounting therefor and particularly pertains 10 to a mirror attachment for auto vehicles and the like.

It is the object of this invention to provide a reflector and a mounting therefor whereby the reflector may readily be attached to the frame of a wind-shield on auto vehicles and the like and adjusted to any desired position and which mounting embodies a bracket and a simple construction whereby the reflector may be disposed 15 at various inclinations relative to the bracket and arranged at any suitable angle thereon so that the reflector may be readily placed in such position relative to the driver of the vehicle as to enable him to conveniently observe in the reflector that region to his rear 20 as may be most desired.

Another object is to provide an adjustment in a device of the above character by means of which horizontal, vertical and 25 pivotal adjustment of the reflector and fastening thereof may be effected by a single clamping element.

A further object is to provide a reflector and a mounting therefor which is simple 30 and economical in construction and adapted to be easily and quickly applied and adjusted.

Other objects will appear hereinafter.

The invention is illustrated in the accompanying drawings, in which:

Figure 1 is a perspective view showing the invention as applied to a wind shield frame.

Fig. 2 is a detail in vertical section showing the manner of disposing the reflector at 45 various vertical angles.

Fig. 3 is a view in horizontal section as seen on the line 3—3 of Fig. 2 showing the manner of adjusting the reflector laterally.

More specifically 4 indicates a bracket one 50 end of which is adapted to be attached to the frame 5 of a wind shield or the like and for which purpose is fitted with a jaw 6 preferably extending at right angles to the bracket and arranged to be positioned 55 against the frame; a clamping jaw 7 being

secured to the jaw 6 by a bolt 8 and nut 9 which clamping jaw is adapted to engage the opposite side of the frame and to be tightened thereagainst in such manner as to securely clamp the bracket on the frame. 60 The outer end of the bracket is bent at right angles and is formed with a vertically extending arcuate plate 10 having a vertical slot 11.

The reflector, indicated at 12, may be of 65 any suitable construction but is here shown as rectangular in form and as fitted with a back wall 14 on which a reflecting surface or mirror is mounted. Projecting from the back wall and extending transversely thereof is an arcuate bar 16 having a longitudinal slot 17 and which bar is adapted to be positioned against the outer arcuate face of the plate 10 and is designed to be adjustably fastened thereto. The connection between 70 the bar and plate is here shown as comprising a pin or bolt 18 which passes through the slots in the plate and bracket and has a head 19 on one end thereof engaging the inner face of the bar. The outer end portion 75 of the bolt is threaded to receive a wing-nut 20 or the like which on being tightened on the bolt will act to clamp the bar and plate together. A split washer 21 is interposed between the wing-nut and the inner arcuate 80 face of the plate and serves to prevent loosening of the nut.

In the application and operation of the invention the bracket is affixed to the frame member 5, being tightly secured thereto by 90 the clamping jaws as before described. The reflector is then adjusted to any desired position on the bracket within its range of movement; the wing-nut being loosened for this purpose. The bar may then be shifted vertically on the arcuate plate with the bolt sliding in the slot in the latter. The plate being curved the reflector may be disposed in either a vertical position as shown in full lines in Fig. 2 or in an inclined position as 100 indicated in dotted lines, the position of the reflector being fixed according to the point of contact of the bar on the plate.

The slot in the bar permits the latter being shifted lengthwise on the bolt and by 105 reason of the arcuate form of the bar the reflector may be disposed at various positions transversely of the vertical plate such for example as parallel therewith as indicated in full lines in Fig. 3 or at an angle 110

relative thereto as indicated in dotted lines. The single connection between the bar and plate effected by the bolt permits the reflector being turned as on a pivot to dis-
5 pose it in either a vertical position as shown in the drawings or in a horizontal or diagonal position should it be desirable to do so. On tightening the wing-nut the outwardly curved face of the bar will be brought into
10 contact with the outwardly curved face of the plate with the portions of the bar on opposite sides of the slot bearing at spaced points on the curved plate thus effecting a wedge-like engagement between the oppo-
15 sitely curved faces so as to insure against disarrangement of the reflector.

From the foregoing it will be seen that I have provided a simple reflector mounting which will permit of a wide range of ad-
20 justment and which by reason of employing a single fastening element may be easily and quickly set to the desired position.

While I have shown and described a specific embodiment of my invention I do not limit myself to the exact details of construction disclosed but may employ such modifications and changes in the several parts and their equivalents as occasion may require and as may come within the scope of the
30 invention as set forth in the accompanying claims.

I claim:

1. In a reflector mounting, a bracket, a vertically extending arcuate plate on said
35 bracket formed with a vertical slot, a re- reflector, a horizontally extending arcuate bar on said reflector having a horizontal slot, said bar arranged to abut against the vertical arcuate plate; a pivot pin extending
40 through the slots in the plate and bar having a head engaging the bar and a wing-

nut screwed on the other end of said pin for clamping the plate and bar together.

2. In a reflector mounting, the combi-
45 nation of a reflector, an arcuate bar on said reflector having a longitudinal slot, a bracket, an arcuate plate on said bracket having a vertical slot, said bar and plate adapted to be arranged against each other with their outwardly curved faces abutting, 50 and means extending through the slots in the bar and plate for adjustably securing said bar and plate together.

3. In a reflector mounting, the combi-
55 nation of a reflector, an arcuate bar on said reflector having a longitudinal slot, a bracket, an arcuate plate on said bracket having a vertical slot, said bar and plate adapted to be arranged against each other with their outwardly curved faces abutting, 60 and means slidably extending through said slots for connecting the bar and plate embodying means for clamping said bar and plate together.

4. A reflector mounting comprising two 65 arcuate members arranged with their out- wardly curved faces abutting, means for clamping said members together in various relative positions, a support for one of said members and a reflector affixed to the other 70 of said members.

5. A reflector mounting comprising two arcuate members arranged with their out- wardly curved faces abutting, each of said 75 members being formed with elongated slots, means passing through said slots for clamp- ing said members together in various posi- tions relative to each other, and on which said members may be turned, a support for one of said members, and a reflector affixed 80 to the other of said members.

JOHN KERN.
